(Cl. D58—11)

To all whom it may concern:

Be it known that I, Nathan E. Morton, a citizen of United States, residing at New York, in the county of New York and State of New York, have invented a new, original, and ornamental Design for a Miniature Bureau for Jewelry, of which the following is a specification, reference being had to the accompanying drawing, forming part thereof.

In the drawing:

Fig. 1 is a front perspective view of my miniature bureau for jewelry showing my new design;

Fig. 2 is a sectional elevational view thereof;

Fig. 3 is a top plan view thereof.

I claim:

The ornamental design for a miniature bureau for jewelry, as shown.

NATHAN E. MORTON.
